UNITED STATES PATENT OFFICE.

CHARLES H. CLARK, OF EASTON, MAINE.

POTATO GRADER.

Application filed March 27, 1925. Serial No. 18,885.

This invention relates to potato graders and has for its object the provision of a simple and inexpensive device whereby the potatoes will be more effectually and rapidly graded than has been heretofore done. The invention is illustrated in the accompanying drawings and will be hereinafter first fully described and then particularly defined in the appended claim.

10 In the drawings:

Figure 1 is a vertical longitudinal section of a potato grader embodying my invention;

Fig. 2 is a plan view of the same, and Fig. 3 is a detail of the screen.

15 Potatoes have been heretofore graded by hand while being caused to flow or roll through a rack or trough, the walls of which converge toward the delivery end of the rack and the bottom of which is composed of 20 slats or bars extending longitudinally of the rack and spaced apart. The open spaces between adjacent bars or slats permitted the loose dirt to pass and also permitted the very small potatoes to drop through, but the separation of the standard size potatoes from the 25 smaller potatoes was performed by hand, the result being that many marketable potatoes were placed with the culls or those of inferior sizes. The object of the invention, 30 therefore, is to provide a simple device by the use of which the potatoes will be effectually graded without being bruised and without requiring an excessive amount of manual labor. In the accompanying drawings, the 35 reference 1 indicates a supporting frame of any convenient construction having side rails 2 secured upon its upper portion, said rails converging toward one end of the frame, as shown in Fig. 2, and extending 40 somewhat beyond the said end of the frame, as shown in Fig. 1. Extending between the rails 2 at the delivery end of the hopper is a solid floor 3 which forms a chute to direct the marketable potatoes into a bag suspended 45 in any convenient manner from the said floor. The inner end of the floor 3 is secured upon a cross bar 4 of the supporting frame and the upper edge of the floor is spaced from the inner or upper edge of said cross 50 bar, as clearly shown in Fig. 1. Another cross bar 5 is secured upon the frame in spaced relation to the cross bar 4 and the slats 6 are secured at their forward ends upon the cross bar 5 and at their rear ends to the frame, as will be readily understood. It will be noted that the slats 6 and the floor

3 are inclined downwardly toward the delivery end of the structure so that the potatoes placed upon the upper ends of the slats will roll down the same toward and over the 60 floor 3. The forward ends of the slats 3 terminate in spaced relation to the forward edge of the cross bar 5 and at the sides of the device abutting the rails 2 filler plates 7 are secured upon the cross bars to span the 65 space between the same immediately adjacent the respective rails. These filler plates are triangular in plan view and their inner sides are parallel and extend longitudinally of the rack. A screen is fitted between these 70 filler plates and comprises an upper head or cross bar 8 adapted to rest upon the cross bar 5 between the filler plates 7, and a lower head or cross bar 9 adapted to rest upon the cross bar 4 between the filler plates. As 75 shown clearly in Fig. 1, the cross bars 8 and 9 abut the ends of the slats 6 and the edge of the floor 3, respectively, and their vertical dimensions are the same as the vertical dimensions of the slats and the floor so that 80 the several parts will be flush when assembled, as shown. Parallel rods 10 extend between the heads or cross bars 8 and 9 and may be provided in such numbers as may be desired. The upper ends of the said rods 85 are fitted into the upper head 8 through the side of the same which is presented to the lower head and the lower ends of the rods are formed with downturned portions 11 which are adapted to fit within the lower 90 head or cross bar 9 through the top of the same. The number of the rods 10 will usually be determined by the size of the rack and the size of the potatoes which it is desired to remove from the bulk of the 95 potatoes, the rods being set at such a distance apart that all the potatoes above a certain diameter will be prevented from dropping between the bars and will roll along the same and out through the delivery end of the 100 rack while those of less diameter will pass between the bars and may be caught in a suitable receptacle supported upon the frame below the screen. To properly guide the potatoes into the said receptacle, a hopper 12 of sheet metal may be secured to the under side of the cross bars 4 and 5, as 105 shown in Fig. 1.

From the foregoing description, taken in connection with the accompanying drawings, it will be readily seen that I have provided a grading screen which may be easily placed

in position and by which the potatoes will be automatically separated according to their sizes as they pass over the screen. The screen is not secured to the supporting frame but is merely placed in position upon the cross bars 4 and 5 and will be held in place by the abutting surfaces of the slats 6 and the floor 3. Inasmuch as the top of the head 8 is flush with the slats 6, the potatoes will not encounter any obstruction in passing from the slats and, consequently, will not be bruised in such transition. The screen rods 10 obviously do not project above the head 8 so that the potatoes may pass from said head onto the rods without being bruised and inasmuch as the rods rise over the forward edge of the lower head 9, the potatoes will be lifted so that they will not roll against a sharp corner of the lower head to be bruised thereby. The lower exposed portions of the screen rods are turned downwardly so as to provide round surfaces to the potatoes as they pass off said rods so that bruising at these points will be avoided.

Having thus described the invention, I claim:

A potato grader comprising a frame having its top inclined throughout its length and comprising an upper slatted portion, a lower imperforate portion and an intermediate open portion, cross bars at the top and bottom of the opening and underlapping the slatted and imperforate portions, respectively, a separating screen in the opening and supported upon the said cross bars, filler plates at the sides of the separating screen, rails at the sides of the slatted, imperforate and screen portions of the frame and converging throughout their length, and a hopper below and opposite the separating screen.

In testimony whereof I affix my signature:

CHARLES H. CLARK. [I. S.]
